UNITED STATES PATENT OFFICE

EVAN W. CROSSAN, OF WILMINGTON, DELAWARE.

STAMPING AND NUMBERING MACHINE.

No. 902,378.

Specification of Letters Patent. Patented Oct. 27, 1908.

Application filed June 23, 1906. Serial No. 323,022.

To all whom it may concern:

Be it known that I, EVAN W. CROSSAN, a citizen of the United States, residing at Wilmington, in the county of Newcastle and State of Delaware, have invented certain new and useful Improvements in Stamping and Numbering Machines, of which the following is a specification, reference being had therein to the accompanying drawing.

10 This invention relates to improvements in adjustable hand stamps or numbering machines of the type wherein a series of printing or character disks or supports are employed, the same being mounted upon a reciprocating yoke or frame and it is the primary object of the invention to provide novel means for readily independently adjusting the printing or character disks or supports.

15 The invention includes novel and efficient means for adjusting the respective printing or character bearing cylindrical disks or supports without the necessity of bringing the hands of the user into contact with said supports.

20 25 The invention further contemplates new and improved means for independently indicating the various positions of the respective printing disks, without having to disarrange the normal position of the machine, to bring 30 into view the characters on the disks themselves.

The invention also comprises an improved inclosing casing for the working parts of the apparatus, and means whereby the positions 35 of the printing disks or supports, are indicated through the upper part of the casing.

Novel means are further provided for separating the usual inking pad from the printing disks or supports and locking the former in 40 its separated position, whereby the adjustment of the disks as above described, will not be hindered or impaired.

Other novel features in the construction and arrangement of parts will be more fully 45 brought out in the detailed description following which should be read in connection with the accompanying drawings, forming a part hereof, and wherein a preferable embodiment of the invention is disclosed for the 50 purpose of illustration.

In the drawings, Figure 1 is a perspective view of the device, Fig. 2 is a side elevation having portions broken away for the purpose of clearness, Fig. 3 is an end elevation, Fig. 4

is a vertical section, Fig. 5 is a detailed view 55 of parts detached for the purpose of clearness.

Referring now more particularly to the drawings wherein like reference characters refer to corresponding parts in the several 60 views, 1, 1 designate oppositely disposed upright supports connected at their upper ends by a cross bar or plate 2 preferably enlarged centrally and having a vertical elongation 3 65 which latter has a longitudinal aperture 3^a therethrough.

4 represents a vertical operating stem arranged to pass through the apertured portion 3^a of the vertical extension 3 and connected to the upper part of a casing 5 fitted 70 between the upright supports and arranged to carry the printing disks or cylinders, together with the adjusting means therefor, all of which to be more particularly described hereinafter. Passing transversely 75 through the stem 4 at a point below the cross bar 2, is a key or pin 6, arranged to pass through a collar 6^a of the casing 5 and detachably secure the casing to said stem, which said latter is preferably hollow for the 80 reception of a spring member 7 arranged to contact at its upper end a knob 8 mounted upon the top of the stem. A convenient support for the lower end of the spring comprises a key 9 mounted upon the vertical extension 3 and passing transversely through oppositely disposed longitudinally extended slotted portions 10 of said stem. The said key 9 is preferably slidable transversely 85 through a slot in said tubular extension, and has enlarged portions 9^a arranged to engage complementary enlarged portions 10^a of said slots, for a purpose to be hereinafter explained.

It will be noted that in normal position the reduced portion of said key is 90 in registration with the slots 10, so that the key will not interrupt the movement of the stem. On the other hand should the stem be moved to a point where the enlarged portions 10^a of the slots are in alinement with 100 the key 9 the stem may be locked in this position by exerting a slight longitudinal movement to the key and thereby bring the enlarged portions 9^a thereof in engagement with said enlarged portions 10^a of the slots. 105

11 designates a cylinder having centrally arranged pintles 12 at its respective ends adapted to pass through oppositely disposed

apertures in the respective sides of the casing 5 and slidably engage within vertically arranged guideways 13 upon the uprights 1, 1. Screws form convenient pintles, as illustrated, the heads extending without the uprights. Upon the cylinder 11 are a series of printing disks 14 fixed against longitudinal movement but independently rotatable in either direction, the said disks carrying upon their periphery numerals, letters or other characters, according to the use of the machine. The periphery of each of said disks 14 is provided with a reduced portion forming an annular shoulder 15 preferably integral therewith and constituting a gear wheel to be engaged by suitable coöperating means, whereby movement may be imparted to the disk 14 without bringing the hands of the user into direct contact therewith.

16 designates a cylinder arranged to pass at its respective ends through openings in the sides of the casing 5, the cylinder having at one end a flange 16^a overlapping the wall surrounding one opening, and at its opposite end a knob or handle 17. The cylinder is rotatable, movement being imparted thereto by the said handle 17 which extends without the casing 5. Mounted upon the cylinder 16 are a series of disks 18, which are termed drive disks for convenience, and correspond in number to the number of printing disks 14. The drive disks are fixed against longitudinal movement but are loose upon the cylinder 16, whereby the latter may rotate independently thereof. Each of said disks 18 has upon its periphery numerals, letters or characters, corresponding to those on the adjacent printing disks 14 and to one side of said disks 18 is arranged a gear wheel 19, preferably integral therewith. Mounted in a longitudinal slotted portion 16^b of said cylinder 16 is a slidable key 20 passing at one end through an aperture in the handle 17 and terminating at said end in a knob 21. At the opposite end of the key is an out-turned dog 22. Each of the disks 18 has a series of notches 20^a around the walls surrounding its openings, the number corresponding to the number of characters on the coöperating printing disk, and spaced accordingly. It is thus seen that the key 20 may be slid longitudinally along the cylinder 18 until the dog 22 is in registration with one of the notches of the disk to which it is desired to impart movement. When in such registration the key constitutes a clutch between the disk and the cylinder. The motion of the gear wheels 19 is transmitted to the printing disks or cylinders 14 through the medium of a series of intermediate disks 23 carrying pinions 24 arranged to engage the gear wheels 19 and gears 25 preferably integral with the pinions, arranged to engage the gears on the flange 15 of the printing disks, the said disks 18 being cut away to al-

low of the movement of the gears 25. The intermediate or transmission disks 23 are rotatably mounted on a shaft 26 mounted on the casing 5.

27 designates an inking attachment, conveniently a pad of ordinary construction normally positioned beneath the lowermost characters on the respective printing cylinders 14. A convenient connecting means for the inking pad comprises arms 28 extending upwardly at an angle at the respective ends of the pad and removably pivoted at their upper ends by a pintle 28^b to an offset portion 28^a of the uprights 1, 1. Links 29 are pivoted at one end to the arms intermediate 75 their ends and at their upper ends to the reciprocating casing 5. It will thus be seen that as the stamp is operated the pad, through the medium of its connection, will be swung adjacent to and away from the operative face 85 of the printing disks.

30 is a base or bottom plate extending between the uprights 1 and connected thereto at their lower ends, the plate having a slot 31 extending longitudinally thereof to admit 90 of the passage therethrough of the several printing characters which are lowermost upon the disks. The casing 5 is preferably constructed of sheet metal and is formed to extend over the respective cylinders and 95 gearing, the same being slotted or cut away longitudinally in its upper portion at 5^a for the purpose of presenting to view the characters appearing upon the respective cylinders 18 and thereby indicate the corresponding character which is in printing position upon the disk 14, the gearing being sized and shaped with this purpose in view, and the cut away portion 5^a being of a width only to expose one character on the respective cylinders at a time, that is the characters which are in alignment.

The operation of the parts thus far set forth may be briefly described as follows: It being desired to change the position of the 110 respective characters on the printing cylinders 14, the operator first imparts downward movement to the stem 4 until the enlarged portions 10^a of the slots 10 are in alignment with the pin or key 9, when the latter will be 115 slid to bring the enlarged portions thereof into engagement with the enlarged portions of the slots, whereby the stem 4 is locked from further movement. In this position it will be noted that the inking pad will have 120 been moved from operative relation to the printing disk by reason of its connection with the casing and uprights, and movement may be imparted to the disks in either direction without contacting the said pad. The key 125 20 is then moved longitudinally within the slot 10 of the casing 5.

Spring actuated dogs 32 of any convenient construction, one for each disk 18 are arranged upon the inner surface of the casing 5 130

and are adapted to engage the gears 19' to prevent accidental movement thereof after being set in desired position.

In order that the key 20 will move but one space at a time, that is a distance equal to the distance between the respective cylinders 18, a spring actuated dog 33 is provided within a slotted portion of the knob 17, the dog being arranged to engage notches or shoulders 34 upon the key, and spaced from one another a distance equal to the space between the adjacent cylinders 18. The dog 33 also operates to retain the key in its adjusted positions.

15 After the parts have been adjusted as above pointed out, the key is released from locking position relative to the stem, when the casing and the several parts carried thereby may be moved downwardly to 20 stamping position by pressing upon the handle 8. The parts are normally held in elevated position by the upward pressure of the spring 7 within the stem.

The casing and the parts carried thereby 25 within may readily be detached from the uprights and operating stem for any desired purpose, when necessary by simply removing the pin 6, screws 12, and pintles 28^b.

I claim:

30 1. In a machine of the character described, a printing wheel, a gear wheel for rotating the printing wheel to bring into operative position the characters thereon, an inclosing casing for said gear wheel, a rotatable cylinder, a drive gear wheel rotatably mounted on the cylinder and meshing with the first-mentioned gear wheel, means for coupling the drive gear to said cylinder to rotate therewith, and indicating means mounted upon 40 the drive gear to one side thereof, the same being viewable from the outside of the casing to indicate the respective positions of said printing wheel.

2. In a hand stamp, oppositely disposed 45 upright supports, a reciprocating printing device including a cylindrical support having at opposite ends pintles arranged to pass through elongated slots in the respective upright supports, printing disks mounted upon 50 said cylindrical support, means for imparting rotary movement to any of said printing disks including a series of disks mounted upon a suitable support, an inclosing casing for said printing disks and operating mechanism, a rod for imparting reciprocatory movement to said casing and the parts carried thereby, means arranged outside of the upright supports to detachably engage the protruding ends of the pintles of the cylindrical 55 support for the printing disk, and a detachable connection between the rod and casing, whereby the parts may be disengaged from said supports.

3. In a hand stamp, a printing device, a reciprocating rod therefor, means for locking

the rod intermediate its limits of movement, including a key arranged to pass through a slotted portion of said rod, the said key having a shoulder thereon arranged to engage with an enlarged portion intermediate the 70 ends of the slot in the rod, an inking attachment for the printing device, means for spacing the inking attachment from the printing device when the rod is in locking position and for adjusting the printing device when the 75 rod is in locking position.

4. In a hand stamp, a frame, a rotatable printing device, a cylindrical support therefor, a reciprocating rod therefor, the rod having a longitudinal slot therein for the 80 passage of a transversely extending guide pin mounted on said frame, the said pin, a spring support for said rod, and the said pin having a part arranged to engage the rod to lock the rod with the parts carried thereby from movement relative to the frame, in combination with a rotatable member carried by the frame and coöperating gearing on the rotatable member and printing device for rotating the printing device, when the rod is locked 85 from movement.

5. In a hand stamp, a frame, an inking pad, a printing device, a reciprocating support therefor, the support having a longitudinal slot therein for the passage of a transversely extending guide pin mounted on said frame, the said pin, the said support being spring pressed, and the said pin being movable and having a shoulder thereon arranged to engage with an enlarged portion intermediate the 95 ends of the slot in the support to lock the same from movement at a point where the printing device will be spaced from the inking pad, and means for adjusting the printing device when thus separated.

105 6. In a machine of the character described, a printing device comprising a plurality of disks having characters on the periphery thereof and a reduced gear portion, a series of rotatable members in engagement with said 110 gear portions for imparting movement to the printing wheels, a cylindrical support for said rotatable members, means on the support for coupling any one of said rotatable members thereto, and a reciprocating support for said printing wheels and rotatable members.

7. In a machine of the character described, a series of rotatable printing disks, means for imparting rotation thereto, including a series 120 of drive wheels, one for each printing wheel, intermeshing gearing on the disks and wheels a cylindrical support upon which said drive wheels are rotatably mounted, means for imparting rotatable movement to the support, 125 and a key mounted on the support for slideable movement arranged to clutch one of said wheels to the support, whereby movement will be imparted to the coöperating printing wheel, a carrier common to said printing disks, 130

driving wheels and support, means for reciprocating the carrier and means for retaining the latter in adjusted position.

8. In a machine of the character described, 5 a series of rotatable printing disks, means for imparting rotation thereto, including a series of drive wheels, one for each printing wheel, a cylindrical support upon which said drive wheels are rotatably mounted, means for imparting rotatable movement to the support, 10 a key mounted on the support for slidable movement arranged to clutch one of said wheels to said support, whereby movement will be imparted to the coöperating printing 15 wheel, and spring actuated means for locking the key in its respective positions.

9. In a machine of the character described, 20 a series of rotatable printing disks, means for imparting rotation thereto, including a series of drive wheels, one for each printing wheel, a cylindrical support upon which said drive wheels are rotatably mounted, means for imparting rotatable movement to the support, 25 a key mounted on the support for slidable movement arranged to clutch one of said wheels to said support, whereby movement will be imparted to the coöperating printing wheel, a series of shoulders on said key equal in number to the number of printing wheels, 30 and a spring actuated dog arranged to engage said shoulders.

10. In a machine of the character described, 35 a series of rotatable printing disks, means for imparting rotation thereto, including a series of drive wheels, one for each printing wheel, a cylindrical support upon which said drive wheels are rotatably mounted, means for imparting rotatable movement to the support, 40 a key mounted on the support for slidable movement arranged to clutch one of said wheels to said support, whereby movement will be imparted to the coöperating printing wheel, spring actuated means for locking the key in its respective 45 positions, and means for retaining the remaining drive wheels from movement.

11. In a machine of the character described, 50 a rotatable printing disk, means for imparting rotation thereto, including a drive wheel, a cylindrical support upon which said drive wheel is rotatably mounted, means for imparting rotatable movement to the support, and means on the support arranged to engage and disengage said drive wheel to 55 clutch the same thereto, and a reciprocating casing upon which said printing disks, drive wheel and coöperating connections are mounted.

12. In a machine of the character described, 60 a series of shiftable printing disks, means for imparting rotation thereto including a series of drive wheels one for each printing disk, having a central aperture with a series of notches in the walls surrounding the 65 same, a cylindrical support upon which said

drive wheels are rotatably mounted, means for rotating the support, spring actuated means for normally retaining the respective wheels from movement, and a key mounted on the support and rotatable therewith, having a dog arranged to engage one of the internal notches of one of the drive wheels to lock the same to said support and rotate the coöperating printing wheel. 70

13. In a machine of the character described, 75 a rotatable printing disk, and means for rotating the same to present different characters appearing thereon to printing position, the said means including a rotatable cylinder, a drive wheel rotatably mounted thereon, means for coupling the drive wheel to the cylinder, and an intermediate transmission wheel the latter being normally geared respectively with the drive wheel and printing disk. 80

14. In a machine of the character described, 85 a rotatable printing disk, means for rotating the same to present different characters appearing thereon to printing position, the said means including a rotatable cylinder, 90 a drive wheel loosely mounted thereon, means for coupling the drive wheel to the cylinder, and an intermediate transmission wheel the latter normally connected respectively with said drive wheel and printing 95 disk, and a reciprocating support for each of said wheels.

15. In a machine of the character described, 100 a series of parallel printing disks independently rotatable, a series of independently rotatable parallel drive disks, one for each printing disk, operative connection between the drive and printing disks, means for imparting movement to any one of said drive disks to independently rotate the same, including a dog slidably longitudinally of and within the drive disks, and spring actuated means in engagement with the drive disks operating to normally retain the same from 105 movement. 110

16. In a hand stamp, oppositely disposed uprights, a series of parallel printing disks, independently rotatable, a series of independently rotatable parallel drive disks, one for each printing disk, a series of independently 115 rotatable parallel transmission wheels arranged intermediate the drive disk and printing disks for transmitting the power of the drive disks to the printing disks, means for imparting movement to any one of said 120 drive disks to operate the coöperating transmission wheels and printing disks, independently of the others, and a casing carrying the said disks, wheels and operating parts, movable longitudinally relative to said 125 uprights.

17. In a machine of the character described, 130 a series of parallel printing disks independently rotatable, a series of independently rotatable parallel drive disks, one for

- each printing disk, operative connection between the drive and printing disks, means for imparting movement to any one of said drive disks independently of the other, including a 5 rotatable cylinder, a handle therefor, and a key for coupling any one of the drive disks to the cylinder, the same being slidably mounted within a slotted portion of the cylinder and extended through the handle and 10 terminating in a knob.
18. In a machine of the character described, a series of printing disks independently rotatable, a series of independently rotatable parallel drive disks, one for each 15 printing disk, operative connection between the drive and printing disks, means for imparting movement to any one of said drive disks independently of the other, including a cylinder and a key slidably mounted in a longitudinally extended slot in the cylinder, the 20 said drive disks having a central opening whereby they are mounted on the cylinder, and a series of notches around said opening, and said key having a dog arranged to engage one of said notches, in combination with 25 means automatically exerting a retarding action on said key at regular intervals as it is slid longitudinally of the cylinder.
19. In a machine of the character described, a series of printing disks independently rotatable, a series of independently rotatable parallel drive disks, one for each printing disk, operative connection between the drive and printing disks, means for imparting 30 movement to any one of said drive disks independently of the other, including a cylinder and a key slidably mounted in a longitudinally extended slot in the cylinder, the said drive disks having a central opening whereby they are mounted on the cylinder, and a series of notches around said opening, and said key having a dog arranged to engage one of said notches, in combination with 35 means for retaining the key in its adjusted 40 positions.
20. In a machine of the character described, a series of printing disks independently rotatable, a series of independently rotatable parallel drive disks, one for each 45 printing disk, operative connection between the drive and printing disks, means for imparting movement to any one of said drive disks independently of the other, including a cylinder and a key slidably mounted in a longitudinally extended slot in the cylinder, the 50 said drive disks having a central opening whereby they are mounted on the cylinder, and a series of notches around said opening, and said key having a dog arranged to engage one of said notches, in combination with 55 means for retaining the key in its adjusted 60 positions comprising a spring actuated dog in engagement therewith.
21. In a machine of the character de- 65 scribed, a series of printing disks independently rotatable, a series of independently rotatable parallel drive disks, one for each printing disk, operative connection between the drive and printing disks, means for imparting movement to any one of said drive 70 disks independently of the other, including a cylinder and a key slidably mounted in a longitudinally extended slot in the cylinder, the said drive disks having a central opening whereby they are mounted on the cylinder, 75 and a series of notches around said opening, and said key having a dog arranged to engage one of said notches, in combination with means for retaining the key in its adjusted position, including a spring actuated dog arranged to engage notches or shoulders on the key, the said notches or shoulders being spaced from one another a distance equal to that between the adjacent drive disks.
22. In a machine of the character de- 80 scribed, a support including uprights and a connecting bar at the upper end thereof, an operating stem slidably mounted in an aperture of said bar, a series of printing wheels, a cylindrical support for the wheels, a supplemental cylindrical support, drive disks for 85 said wheels on the supplemental support, detachable pintles at opposite ends of said cylindrical support for the printing wheels slidably mounted in elongated slots in said uprights, an inclosing casing for said cylindrical supports, printing wheels and disks, and a detachable connection between said casing and said operating stem.
23. In a machine of the character de- 90 scribed, upright supports and a connecting bar at the upper end thereof, an operating stem slidably within an aperture of said bar, a cylindrical support, a series of printing 95 wheels loosely mounted for rotation in either 100 direction upon said cylindrical support, an inclosing casing for said cylindrical support and printing wheels, means for imparting rotary movement to said wheels including a series of disks upon a support within said casing, said disk support, a connection between said casing and operating stem, and pintles at the respective ends of said cylindrical support passing through said casing and slidably 105 within longitudinally extended slotted portions of said upright supports.
24. In a hand stamp, oppositely disposed upright supports, a reciprocating printing device including a series of rotatable wheels mounted within said support, a series of rotatable drive disks one for each wheel also mounted within the support, an inking device, and means connected with said inking device, for retaining the same in inking position relative to said wheels when the latter 115 are in their uppermost position, and for spacing said inking device from said wheels 120 when downward movement is imparted.
- 25.

thereto, the said means including arms extending upwardly at an angle at the respective ends of the inking device pivoted to the said upright supports, and links pivoted to said arms intermediate their ends and to a casing carried by said wheels, and the said casing.

In testimony whereof I affix my signature in presence of two witnesses.

EVAN W. CROSSAN.
